UNITED STATES PATENT OFFICE.

JOSUA SALZBERGER, OF NEW YORK, N. Y.

FUR CHENILLE.

1,119,120.

Specification of Letters Patent.

Patented Dec. 1, 1914.

Application filed January 18, 1913. Serial No. 742,865.

To all whom it may concern:

Be it known that I, JOSUA SALZBERGER, a citizen of the United States, residing at New York city, borough of Bronx, in the county of New York and State of New York, have invented certain new and useful Improvements in Fur Chenilles, of which the following is a specification.

My invention relates to improvements in chenilles, and more especially to that of fur chenilles.

The object of my invention is to produce a fur chenille cheaply by using the discarded scraps of fur garment manufacturers.

A further object is to be enabled to use said scraps no matter in what condition they have been cut, and adapt the same to be quickly made into fur chenilles at a minimum cost.

The invention consists in structural features and arrangement of parts which will hereinafter be more fully described and particularly pointed out in the appended claims.

In the drawings where similar reference characters correspond to the same parts in the different figures; Figure 1 represents a series of disconnected sections of fur of uniform width; Fig. 2 represents the under side of the scraps shown in Fig. 1, fastened together; Fig. 3 shows the fur side of the scraps secured together as shown in Fig. 2; Fig. 4 is a view of the flexible core used in making the chenille; and Fig. 5 is an elevation of a section of the finished chenille.

Referring to the drawings 1, 1^a, 1^b and 1^c represent sections of fur scraps which have been so trimmed as to be of uniform width, as shown in Fig. 1. These sections are sewed together as shown at 2 or they may be attached in any suitable manner as by glue or paste, as shown at 3, or by small staples as at 4. I wish it to be distinctly understood that I do not limit myself to the particular fastening means herein shown, but any other suitable expedients may be employed to secure the ends. It will be seen from Fig. 2 that I first form a tape or strip of fur of uniform width composed of a series of connected sections of fur. After a tape 6 of proper length has been made, see Fig. 3, one end of this strip is fastened

by any suitable means to one end of a flexible core 5 of any diameter, (see Fig. 5), with the fur side outward. The end of the core 5 having the fur strip attached thereto is then so secured that it may turn when the core is rotated. The fur strip is then spirally wound around the core 5 by twisting or turning the core, when the fur strip will become tightly and uniformly wrapped around said core, (see Fig. 5), with the backing of the fur adjacent to the core and the edges of said backing being contiguous and arranged spirally around the core, and when the proper length of tape has been formed, its end may be secured to the core by any suitable means. The contiguous edges of the backing arranged spirally around the core are hidden from view by the fur overlapping the edges, making the chenille appear as a continuous cylinder of fur. These lengths, as will be readily seen, can be made of any number of yards, and by simply sewing together small pieces or sections of fur which have been discarded by the furriers or garment manufacturers. If so desired the tape of fur may be secured to the core by means of paste or other adhesive material placed on the core, as shown for example at 7 in Fig. 5, before the tape is wound upon the same.

From the foregoing description it will be seen that a fur chenille can be quickly and cheaply manufactured by the utilization of scraps of fur which have heretofore been wasted or discarded. It will also be understood that the chenille herein shown and described can be readily used in making fur garments, as for example, muffs, coats, stoles, and other similar articles, by sewing or weaving together the chenille herein shown and described.

What I claim is:—

1. As a new article of manufacture a fur chenille consisting of a flexible core having a strip of fur with its backing of uniform width secured adjacent to and with said core, and the fur surface on the outside, and the edges of the backing arranged contiguously and spirally around the core, and the fur covering the edges of the backing.

2. As a new article of manufacture a fur chenille consisting of a flexible core having

a strip of fur of uniform width with its
backing spirally wound adjacent upon said
core and the fur surface on the outside, the
edges of the backing arranged contiguously
5 and spirally around the core, and the fur
covering the edges of the backing.

In testimony whereof I affix my signature
in presence of two witnesses.

JOSUA SALZBERGER.
